UNITED STATES PATENT OFFICE.

GEORGE E. SCHNEIDER, OF SAN FRANCISCO, CALIFORNIA.

GARBAGE-INCINERATOR.

1,282,638.

Specification of Letters Patent.

Patented Oct. 22, 1918.

Application filed July 18, 1917. Serial No. 181,253.

To all whom it may concern:

Be it known that I, GEORGE E. SCHNEIDER, a citizen of the United States, residing in the city and county of San Francisco and State of California, have invented certain new and useful Improvements in Garbage-Incinerators, of which the following is a specification.

My invention relates to the class of garbage-incinerators.

The object of the invention is to provide a furnace capable of generating sufficient heat to thoroughly dry the garbage and to deliver it in its dried state to the fire wherein it is consumed, and during the operation of drying, to remove the volatile products from the charge, separate from said products the condensable portions, and deliver the uncondensable portions under pressure to the fire, for consumption, the whole device during operation being effectually closed to the escape of all vapors and odors.

To this end my invention consists in the novel garbage incinerator which I shall now fully describe by reference to the accompanying drawings in which,

Figure 1 is a vertical longitudinal section, broken and partly in elevation, of my garbage incinerator.

Fig. 2 is a head-end view of the same.

Fig. 3 is a cross-section on the line 3—3 of Fig. 1.

Fig. 4 is a foot-end view of the device.

Fig. 5 is a broken plan view of the head-end of the incinerator on the line 5—5 of Fig. 4, enlarged.

1 is the main setting, having in its lower portion the fire chamber 2, with fire-flue 3, and grate 4, under which is the ash pit 5 adapted to receive a discharge car 6.

The roof 7 of the fire flue 3 is arched as seen in Fig. 3, and the brick work or setting of this arch is continued to form an arched inclosure or housing 8 for the revolving drum 9. Between the arch of the housing 8 and the arched roof 10 of the main setting is a space 11 to afford entrance to workmen for repairs.

In the walls of the main setting 1 are the flues 12, the lowermost of which communicate as seen in Fig. 1 at 13 with the fire flue 3, and thence said flues continue inclining or zig-zagging upwardly, as seen by the dotted lines in Fig. 1 to the stack 14. Thus an extensive course is afforded for the products of combustion, giving time for the settling

out of undesirable and offensive matters and odors. Access to these flues 12 is had through the end plates 15, seen in Fig. 2, each plate covering the end communication of a pair of flues.

The drum 9 is an elongated cylindrical structure, set at an inclination from head to foot and having on its interior the lifting and stirring flanges 16. Said drum is mounted wholly within the arched housing 8 being carried upon rollers 17, and having a rotary motion imparted to it by means of a gear 18 on each end. Power is led in from the pulley 19, see Fig. 5, to a side shaft 20, carrying at each end a bevel gear 21. These bevel gears mesh with bevel gears 22 on shafts 23, which carry at their other ends bevel gears 24 meshing with bevel gears 25 on short countershafts 26, the latter having gears 27 meshing with the gears 18 on the drum ends.

In the head end of the drum 9 is a feed gate 28, Figs. 1 and 2, with side wings 29, adapted when the gate is opened outward to form a closure with the feed hopper 30. This hopper is supplied either by direct dumping through a top gate 31, or by means of an elevator 32, shown in Fig. 1. In the head end of the drum is also an air opening 33, controlled by a sliding damper 34, Fig. 2. At the foot of the drum is a discharge gate 35 against and in contact with which the drum rotates. This gate is hung from a hollow arm 36, the upper end of which is axially pivoted upon the driving shaft 37 of the fan 38, as seen in Fig. 4. The upper end of the hollow arm 36 communicates with the suction side of the fan 38, and the lower end communicates with the interior of the drum. Said gate, therefore swings to and from its contact with the drum, being normally closed by gravity and adapted to be swung to an open position by suitable means, as for example, by a block and tackle not shown. The compression side of the fan 38 communicates by means of a pipe 39 with a condenser 40 containing a cooling coil 41. The top of the condenser is fitted with a pipe 42 controlled by a valve 43, said pipe entering the stack 14. This pipe also communicates through a pipe 44 with a tank 45 on top of the main setting 1. A baffle plate 46 is fitted under the end of the pipe 44 within the tank. From said tank 45 leads a pipe 47 down to a nozzle 48 extending into the fire chamber 2. The bottom of the con-

denser 40 has an outlet pipe 49 from which leads a controllable discharge pipe 50, to any suitable destination.

In the wall of the main setting 1, above the fire chamber 2 is a chute 51 lying under the foot of the drum. This chute has a top hopper 52 and is controlled by an inclined gate 53 adapted by means of a handle 54 to be slid back and forth to cover and to 10 cover the chute 51. The gate 53 slips sufficiently freely through the wall of the hopper 52, to provide for the escape from the hopper, over the surface of the gate when closed, of liquid condensations, into the pan 55 from 15 which a delivery pipe 56 leads.

Secured to the foot discharge gate 35 is a hood 57 which at its upper end opens into the drum while its lower end normally covers the pan 55 and the hopper 52.

20 In Figs. 1 and 4, 58 indicates a fuel burner as the source of heat.

The operation of the device is as follows:

Heat is supplied from the burner 58. The garbage is supplied to the hopper 30 and by 25 the hopper is fed to the drum 9 through its feed gate 28. When the drum is charged, the supply of garbage is arrested and the feed gate 28 is closed. The drum being rotated, the garbage is kept stirred up by the 30 flanges 16 in the drum. As the garbage is heated, the volatile products are driven off and are sucked out through the hollow arm 36 by the fan 38 and by said fan are forced into the condenser 40. Such of these volatile 35 products as are condensable are trapped from the base of the condenser and led away through the delivery pipes 49 and 50. Such of the products as do not condense are forced by the fan from the condenser through the 40 pipe 44 into the tank 45, from which they are driven through the pipe 47 and nozzle 48 into the fire chamber 2, wherein they are consumed. As these volatile products enter the tank, their velocity is sufficiently slowed 45 up, assisted by the baffle 46, to enable such condensable portions as may remain, to separate out. As the operation proceeds and the drum contents become drier, the decreasing volume of vapors may be allowed to pass directly into the stack 14 through the valve 43.

At the beginning of and during the operation such liquid condensations as may settle from the drum contents trickle out from the foot of the drum, past the foot of the gravity 55 gate 35 and run down into the hopper 52 and upon the closed slide gate 53. From this gate they flow to the pan 55 and are carried off by the pipe 56. The hood 57 effectively confines their odors and carries them 60 back into the drum.

When the drum contents are bone dry, the foot gate 35 is swung back to open the drum, and the slide gate 53 is withdrawn. The dry material then passes by gravity from the inclined drum 9 into the hopper 52 and falling

through the chute 51 is delivered directly into the fire and is consumed.

The products of combustion from the furnace, by their long passage through the zig-zag flues 12 are relieved of their objectionable matters which settle out and may be cleaned from the flues through the end plates 15, thus leaving the products, which finally pass from the stack, relatively innocuous or unobjectionable. The drum by being wholly 70 housed within the arches or secondary setting 8 is protected from the direct fire and will therefore be durable. During operation the several closures, namely the gates 28 and 35, the hood 57 and the closed vapor passages, effectually confine and keep under control all odors and thus remove the objectionable feature of incinerating garbage. 75 80

I claim:

1. A garbage incinerator comprising a 85 main setting containing a fire chamber with a fire-flue leading therefrom, said main setting having in its walls an uprising series of connected zig-zag flues leading from the fire-flue; a stack with which said 90 series of zig-zag flues communicate; a secondary setting within the main setting subject to exterior heat from the fire chamber; an inclined rotatable heating drum for the garbage, wholly housed within the secondary setting; means associated with the head of the drum to charge it with garbage; and controllable means associated with the foot of the drum for delivering the dried 95 garbage into the fire chamber. 100

2. A garbage incinerator comprising a setting containing a fire chamber; a heating drum housed within the setting and having at one end a feed gate adapted to admit and confine a charge of garbage within the 105 drum; a delivery gate at the other end of the drum; a chute associated with said drum end and gate said chute leading into the fire chamber, and a hood carried by the gate, said hood opening at its upper end through the gate into the drum and at its lower end covering the communication of the gate with the chute. 110

3. A garbage incinerator comprising a setting containing a fire chamber; a heating drum housed within the setting and having at one end a feed gate adapted to admit and confine a charge of garbage within the drum; a delivery gate at the other end of the drum; a chute associated with 115 said drum end and gate said chute leading into the fire chamber; and a hood carried by the gate, said hood opening at its upper end through the gate into the drum and at its lower end covering the communication of the gate with the chute; a fan communicating on its suction side with the drum; and connections with the pressure side of the fan, leading into the fire chamber. 120 125

4. A garbage incinerator comprising a 130

setting containing a fire chamber; a heating drum housed within the setting and having at one end a feed gate adapted to admit and confine a charge of garbage within the

into the fire chamber; a hood carried by the gate for covering the chute communication; and connections with the pressure side of the fan, leading into the fire chamber. 35

5 drum; a delivery gate at the other end of the drum; a chute associated with said drum end and gate said chute leading into the fire chamber, and a hood carried by the gate, said hood opening at its upper end 10 through the gate into the drum and at its lower end covering the communication of the gate with the chute; a fan communicating on its suction side with the drum; a condenser with which the pressure side of 15 the fan communicates; a separating tank with which the condenser communicates; and a pipe leading from the tank into the fire chamber.

6. A garbage incinerator comprising a setting containing a fire chamber; a drum housed within said setting and having means at one end to control the admission of the charge and confine it; a fan; a closing 40 gate controlling the other end of the drum, said gate being pivotally suspended from the fan shaft by a hollow arm communicating at one end through the gate with the drum interior and at the other end communicating with the suction side of the fan; a chute associated with the gate and discharge end of the drum adapted to convey the drum contents into the fire chamber; a hood carried by the gate for covering the chute communication; a condenser with which the pressure side of the fan communicates; a separating tank with which the condenser communicates; and a pipe leading from said 45 tank into the fire chamber. 50

In testimony whereof I have signed my name to this specification in the presence of two subscribing witnesses.
